COVER FOR ELEVATOR DOOR HANGER
MECHANISM

Harry William Larson, Jamestown, N. Y., assignor
to Art Metal Construction Company, Jame-
stown, N. Y.

Application April 3, 1941, Serial No. 386,693

1 Claim. (Cl. 16—95)

This invention relates to improvements in cover means for the hanger mechanisms of elevator doors.

The hanger mechanisms or means for slidably mounting the doors of elevator shaft doorways are usually housed in pockets or chambers provided in the inner sides of the front walls or structures of the elevator shafts above the door openings. At present most manufacturers of elevator doors provide the containing pockets or chambers for the door hangers and their tracks with covers or closure means, which may consist of a large, single-piece, metal cover or separate cover sections, that are hinged or made removable in order to afford access to the hanger mechanisms for servicing the same. These covers as heretofore constructed, whether in a single piece or in sections, unless special care is exercised to tightly secure them in place, are apt to be or become loose so that they are caused to rattle and make objectionable noise, due to the suction or vibration produced by the travel of the elevator cab in the shaft. The servicing is ordinarily done only at infrequent intervals of several months apart, and the covers become dirty and greasy. Since provision must be made for disposal of the dirty removable covers during the time that the servicing work is being done, it is not desirable for workmen to perform the servicing operations from within the elevator cab. This, and the difficulty of opening or handling and replacing the covers, requires the work to be done by one or more workmen on the top of the cab, and in the case of the large, single-piece covers, which some times are over five feet long, the services of two men on top of the cab are required to remove and replace the covers when servicing the hanger mechanisms. It is difficult to properly replace the long covers and there is always the possibility that one may be improperly replaced or insecurely fastened, which would result in a loose condition, with consequent objectionable noise.

The objects of this invention are to provide a practical and desirable cover for the elevator door hanger mechanisms of improved, novel construction, which will overcome these objections and enable ready and easy access to the mechanism for servicing purposes; which will insure a tight closure of the cover and prevent objectionable noise; and which makes it possible for the servicing operations to be performed easily and conveniently by a person working inside of the elevator cab.

Further objects and advantages of the inven-

tion will appear from the following specification of the preferred embodiment of the invention, shown in the accompanying drawings, and the novel features of the invention are set forth in the appended claim.

In said drawings:

Fig. 1 is a fragmentary elevation of the front wall or structure of an elevator shaft as seen from inside the shaft, provided with cover means embodying my invention, for the door hanger mechanism.

Fig. 2 is a sectional plan view thereof on line 2—2, Fig. 1, this figure, like Fig. 1, showing the cover means applied to an elevator door unit of the two speed or differentially travelling double door type.

Figs. 3 and 4 are similar sectional plan views, but illustrating applications of the invention to elevator door units of the central opening and single slide types respectively.

Fig. 5 is a transverse, sectional elevation, enlarged, on line 5—5, Fig. 1.

Figs. 6 and 7 are sectional elevations of the cover means on a still larger scale, on lines 6—6 and 7—7 respectively, Fig. 1.

Fig. 8 is a sectional plan view on line 8—8, Fig. 6, showing one of the anti-rattling springs for the cover door.

Referring first to the Figs. 1 and 2 embodiment of the invention:

10 indicates, in general, the front wall, frame or structure of elevator shaft, 11 the door opening therethrough, and 12 and 13 the two elevator doors adapted to slide at different speeds in one direction for opening the doors and in the opposite direction for closing them. The elevator shaft may be of any usual or suitable construction which provides the necessary elevator door opening and pocket or chamber above the door opening for the hanger mechanism for the doors. As illustrated in the drawings, the front of the elevator shaft structure includes upright jamb or side members 14 and 15 at opposite sides of the door opening 11, an upright supporting member 16 spaced to one side of the door opening, and a horizontal head beam or lintel member 17 extending horizontally above the door opening and secured to the upright members 14, 15 and 16. The head beam or member 17 shown, which is of a form commonly employed for the purpose, has upright and horizontal web portions forming a pocket or space for the door hangers and their supporting track (not shown) a forwardly projecting, horizontal lower flange 18 over the door opening 11, and a flange 19 which extends

upwardly from the rear edge of the horizontal web portion of the beam 17 and to which the usual facing plate 20 of the shaft is connected.

The cover which closes the rear side of the pocket or space 21, in which the hanger mechanism is located, and covers or projects the hanger mechanism, comprises a horizontally elongated, vertical metal plate 22 which extends horizontally from one to the other of the upright members 14 and 16 of the shaft structure, and is provided with an opening 23 therethrough affording access to the hanger mechanism and adapted to be closed by a sliding door or plate 24. The cover plate 22 is preferably secured in place by tongues or clips 25 at its ends projecting into and releasably engaging the lower edges of slots 26 in the structural upright members 14 and 16, and screws 27 which fasten the upper edge of the plate to the top flange 19 of the head beam 17. This cover plate is thus stationarily secured in position but can be easily removed if occasion demands by removing the screws 27 and disengaging the clips 25 from the slots 26. However, the cover plate 22 does not have to be removed for ordinary servicing operations on the door hanger mechanism and ordinarily remains secured in place, such ordinary servicing being performed through the opening 23 by simply sliding back the door plate 24 to uncover the opening. The door plate 24 is mounted on the cover plate 22 to slide horizontally thereon in suitable guides preferably formed by channel members 28 welded or otherwise suitably fixed to the front or inner side of the cover plate 22 above and below the opening 23 so that the door plate 24 can be slid horizontally from a position in which it covers the opening to a side position in which it uncovers the opening to afford access therethrough to the hanger mechanism in the pocket 21.

In order to prevent looseness and rattling of the door plate 24, spring means are provided which press the door plate 24 yieldingly against its guides. Spring tongues or strips 30 are shown for this purpose, each riveted at one end to the door plate, at the top and bottom edge portions thereof, with the spring tongues arranged to slide and bear yieldingly against the outer flanges of the guide channels 28. The free portion of each spring tongue is preferably of ogee or S curvature, having convexed portions adapted to bear against both the face of the door plate and the opposed flange of the guide channel 28 so as to effectually press the door plate yieldingly against the other flanges of the guide channels. Thus, looseness and rattling of the door with consequent noise, due to the suction

or vibration caused by the movement of the elevator cab, is prevented. A socket 31 is shown in the door plate in which a tool can be inserted to serve as a handle for opening and closing the door.

The door opening 23 of the cover plate should, of course, be of such size and so located as to afford most convenient and adequate access to the hanger mechanism for servicing purposes.

10 In the above described embodiment which refers to an installation for the two speed doors, the cover opening 23 can be located, as shown, over the inner of the two doors only, since with this type of door, both door hanger mechanisms can be brought opposite the opening.

In the single door embodiment illustrated in Fig. 4, the construction may be like that described, except that the cover opening 23a is made practically the full width of the elevator door and is located above the door when it is closed. This construction requires more room at one side of the cover opening to enable the necessary movement of the longer cover door to completely uncover the opening.

25 In the center opening elevator door embodiment shown in Fig. 3, the construction differs from the others principally in that the cover opening 23b extends for approximately the full width of the elevator door opening and the cover door is made in two sections 24b arranged to slide to opposite sides of the opening for uncovering it.

I claim as my invention:

35 In an elevator structure in which the hanger mechanism for a sliding elevator door is enclosed in an elongated chamber extending horizontally above the elevator door, closure means for said chamber comprising a horizontally elongated cover secured in place over and covering 40 that side of said chamber which faces toward the elevator cab, said cover having an opening therethrough to afford access to the hanger mechanism within said chamber, horizontal guides on said cover adjacent the top and bottom edges of 45 said opening and extending beyond an end of the opening a distance equal to a substantial portion of the length of said opening, a door plate slidably supported by said guides to slide horizontally to and from a closed position in which it covers said opening to an open position at one side of said opening, and spring tongues secured to said door plate and each slidably bearing against one of said guides for yieldingly pressing the door plate against said guides to 50 prevent rattling of the door plate.

HARRY WILLIAM LARSON.
